UNITED STATES PATENT OFFICE.

HARVEY R. NEWQUIST, OF SAN DIEGO, CALIFORNIA.

COMBINATION LOCK-WASHER TOOL AND SOCKET WRENCH.

Application filed April 3, 1924. Serial No. 703,919.

To all whom it may concern:

Be it known that I, HARVEY R. NEWQUIST, a citizen of the United States, residing at San Diego, in the county of San Diego and 5 State of California, have invented certain new and useful Combination Lock-Washer Tools and Socket Wrenches, of which the following is a specification.

My invention relates to a combination 10 lock washer tool and socket wrench, which is particularly adapted for clinching and straightening the lock washers of the bolts holding the Bendix spring of an automobile in position, and for removing said bolts, and 15 the objects of my invention are: First, to provide a device of this class whereby the bolts, holding the Bendix spring of an automobile starting mechanism in position, may be easily removed and whereby the conventional lock washer holding said bolts from 20 turning may be easily released from positive engagement with the bolt heads from the outside of the casing enclosing said portion of the starting mechanism; second, to provide a device of this class whereby said lock 25 washers, adapted to hold said bolts from turning, may be easily clinched or bent upwardly in positive engagement with the bolt heads; third, to provide a device of this class 30 which is adapted to facilitate the clinching and straightening of the locking lugs of washers of the type described, and which is also adapted to facilitate the removal of bolts and nuts thus locked or adapted to be 35 locked; fourth, to provide a novel means for straightening lock washers of the class described; fifth, to provide a novel cam actuated means for clinching said lock washers 40 against the sides of nuts or the heads of bolts; sixth, to provide as a whole a novelly constructed device of this class, and seventh, to provide such a device which is very simple and economical of construction, durable, 45 easy to operate, and which will not readily deteriorate or get out of order.

With these and other objects in view, as will appear hereinafter, my invention consists of certain novel features of construction, combination and arrangement of 50 parts and portions, as will be hereinafter described in detail and particularly set forth in the appended claims, reference being had to the accompanying drawings and to the characters of reference thereon, which form 55 a part of this application, in which:

Figure 1 is a front view of my combina-

tion lock washer tool and socket wrench, showing the actuating member thereof in a position to remove the locking lug of the lock washer from positive engagement with the head of a bolt adapted to hold a Bendix spring in positive position; Fig. 2 is a side elevational view thereof, showing certain parts and portions of the socket member broken away and in section to facilitate the illustration; Fig. 3 is a perspective view of the lock washer; Fig. 4 is a fragmentary front elevational view of my device, showing the actuating member in a position to receive the locking lug of the lock washer preparatory to clinching the same against the head of a bolt or nut; Fig. 5 is a fragmentary side elevational view thereof, showing the same in position on a bolt head and showing certain parts and portions of the actuating and socket members broken away and in section to facilitate the illustration, and Fig. 6 is a top view of my device, showing the actuating handle fragmentarily by dotted lines in a certain releasing position.

Like characters of reference refer to similar parts and portions throughout the several views of the drawings.

The socket member 1, actuating member 2, actuating member retaining screws 3, socket member handle 4, actuating cam 5, pivot screw 6, actuating cam handle 7, and the lug 8, constitute the principal parts and portions of my device.

The socket member 1 is preferably made long so that the same may be inserted into small and deep recesses, and the same may be made of any desired cross-section, but is preferably provided with a flat side against which is positioned and reciprocally mounted the actuating member 2, which is retained in position relatively thereto by means of screws 3. At the one end of the socket member 1 is provided a polygonally shaped recess 1^a, which is adapted to receive a nut or the head of a bolt B, there being provided an additional, reduced, inwardly extending recess 1^b which is adapted to receive the shank of a bolt when the socket member is positioned over a nut. Said polygonally shaped recess 1^a is so positioned to one side in the end of the member 1 that one of the flat sides of the nuts or bolt heads adapted to be positioned therein come substantially flush with the one flat side of the socket member 1 against which the member 2 is positioned. The actuating member 2 is pro-

vided with longitudinal slots 2^a, through which the screws 3 extend, and which permit the member 2 to be shifted longitudinally relatively to the member 1. The normally lower end 2^b of the actuating member 2 is beveled and serves as a wedge between the clinched or upwardly bent locking lug W¹ of the washer W and the nut or the head of the bolt adapted to be positioned in the recess of the socket member 1.

In order to straighten the washer W or bend the locking lug W¹ thereof downwardly, the actuating member 2 is shifted to the extreme upward position, shown in Figs. 1 and 2 of the drawings, and the socket member 1 is positioned over the nut or bolt head. The upper end of the actuating member 2 is then struck with a hammer, which operation bends the locking lug W¹ outwardly and downwardly and permits the bolt or nut to be removed.

The socket member 1 is provided at its upper end with an outwardly extending handle 4, whereby said socket member may be rotated for removing the bolt B.

At the upper end of said socket member is pivotally mounted an actuating cam 5 by means of a pivot screw 6, as shown best in Fig. 6 of the drawings. A handle 7 is secured to and extends outwardly from the actuating cam 5 for rotating the same. At the one side of the cam member 5 is provided a helical cam portion 5^a, which is adapted to be engaged by a cam lug 8 secured at the upper portion of the inner sides of the actuating member 2.

When desiring to clinch the locking lug of the washer W against the flat side of a nut or bolt head, the actuating member 2 is shifted to its extreme downward position, with the handle 7 in the extreme counterclockwise position as shown by dotted lines in Fig. 6. The recess portion of the socket member 1 is then positioned over the head of the bolt or the nut, with the locking lug W¹ of the washer extending through the lower elongated slot 2^a of the actuating member 2, as shown in Fig. 5. It will be noted that the lower end of the lower elongated slot 2^a is flat, as indicated by 2^c in Fig. 4, and is slightly rounded at its inner edge, as indicated by 2^d in Fig. 5. When the actuating member 2 is in the position shown in Figs. 4 and 5 of the drawings, the lower end of the cam lug 8 is in engagement with the lower end or portion of the helical cam portion 5^a of the actuating cam 5. When the device is in the position stated, the actuating cam is then rotated from the position shown by dotted lines of the handle in Fig. 6 of the drawings, to that shown by solid lines, which raises the actuating member 2, bending the locking lug W¹ of the washer W upwardly and clinching the same against the flat side of the bolt head or

nut. It will be here noted that the outer side of the actuating member 2 contiguous to the lower screw 3 is cut away, as indicated by 2^e in Figs. 2 and 5, which permits the actuating member 2 to be shifted outwardly a slight distance when the portion of the actuating member between the lower end of the lower slot 2^a and the lower end of said member is forced beyond and over the locking lug of the washer W. It will also be here noted that the lower end of the actuating member 2 is of substantially the same thickness as the distance between the head of the lower screw 3 and the flat side of the socket member 1, so that the lower end of said actuating member is held in close proximity to the head of the bolt or nut when straightening or bending the locking lug W¹ downwardly.

It is obvious from this construction, as illustrated in the drawings and disclosed in the foregoing specification, that there is provided a combined lock washer tool and socket wrench as aimed at and set forth in the objects of the invention, and though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent, is:

1. In a tool of the class described, a socket member provided at one end with a recess adapted to receive a bolt head or nut, and an actuating member shiftably mounted at one side thereof and provided at its lower portion with a wedge portion adapted to be inserted between the locking portion of a lock washer and said bolt head or nut.

2. In a tool of the class described, a socket member provided at one end with a recess adapted to receive a bolt head or nut, and an actuating member shiftably mounted at one side of said socket member and provided near its one end with a flat portion adapted to engage the under side of the locking portion of a lock washer.

3. In a tool of the class described, a socket member provided at one end with a recess adapted to receive a bolt head or nut, an actuating member shiftably mounted at one side of said socket member and provided near its one end with a flat portion adapted to engage the under side of the locking portion of a lock washer, and a cam means at the upper portion of said socket member adapted to engage and shift said actuating member.

4. In a tool of the class described, a socket

- member provided at one end with a recess adapted to receive a bolt head or nut, an actuating member shiftably mounted at one side of said socket member and provided 5 near its one end with a flat portion adapted to engage the under side of the locking portion of a lock washer, and a cam member provided with an outwardly extending handle pivotally mounted at the opposite end 10 of said socket member and adapted to engage a cam lug near the one end of said actuating member for shifting the latter.
5. In a device of the class described, a socket member provided at its one end with 15 a polygonally shaped recess, and an actuating member reciprocally mounted at one side of said socket member and provided at its lower end with a wedge portion adapted to be driven between the locking portion of a 20 lock washer and the nut or the head of the bolt positioned in the recess of said socket member.
6. In a device of the class described, a socket member provided at its one end with 25 a polygonally shaped recess, an actuating member reciprocally mounted at the one side of said socket member and provided near its lower end with a slot having a flat portion, and means for shifting said actuating 30 member relatively to said socket member.
7. In a device of the class described, a socket member provided at its one end with 35 a polygonally shaped recess, an actuating member reciprocally mounted at the one side of said socket member and provided near its lower end with a slot having a flat portion, and a cam member provided with an outwardly extending handle rotatably mounted at the normally upper end of said socket 40 member, said cam member being adapted to engage a cam lug at the upper portion of said actuating member for shifting the latter relatively to said socket member.
8. In a device of the class described, a socket member provided at its lower end 45 with a polygonally shaped recess adapted to receive a bolt head or a nut, the one side of the wall forming said recess being removed, permitting the one side of the bolt head or 50 nut positioned in said recess to come substantially flush with the one side of said socket member, and an actuating member reciprocally mounted at said one side of the socket member contiguous to said recess and 55 provided at its normally lower end with a wedge portion adapted to be inserted be-
- tween the locking portion of a lock washer and the one side of the bolt head or nut positioned in said polygonally shaped recess.
9. In a device of the class described, a 60 socket member provided at its lower end with a polygonally shaped recess adapted to receive a bolt head or a nut, the one side of the wall forming said recess being removed, permitting the one side of the bolt head or 65 nut positioned in said recess to come substantially flush with the one side of said socket member, an actuating member reciprocally mounted at said one side of the socket member contiguous to the recess 70 therein and provided near its lower end with an elongated slot provided with a flat bottom end rounded at its inner edge, and means for reciprocating said actuating member.
10. In a device of the class described, a socket member provided at its lower end with 75 a polygonally shaped recess, the one side of the wall forming said recess being removed, permitting the one side of the bolt head or nut positioned in said recess to come substantially flush with the one side of said socket member, an actuating member reciprocally mounted at said one side of the 80 socket member contiguous to the recess therein and provided near its lower end with an elongated slot provided with a flat bottom end rounded at its inner edge, and means for reciprocating said actuating member.
11. In a tool of the class described, a socket member provided with a recess adapted 85 to receive a bolt head or nut, and an actuating member shiftably mounted at one side of said socket member and provided near its one end with an abutment portion adapted to be shifted past one side of said recess and adapted to engage the under side 90 of the locking portion of a lock washer.
- In testimony whereof, I have hereunto set my hand at San Diego, California, this 29th day of March, 1924.

HARVEY R. NEWQUIST.
